(57) CLAIM

The ornamental design for a ring light, as shown and described.

DESCRIPTION

FIG. 1 is a first perspective view of a ring light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the ring light thereof;

FIG. 10 is an enlarged view of the selected portion in FIG. 1;

FIG. 11 is an enlarged view of the selected portion in FIG. 1; and,

FIG. 12 is an enlarged view of the selected portion in FIG. 2.

The broken lines shown in the drawings depict portions of the ring light in which the design is embodied that form no part of the claimed design.
